H. H. MERCER

STEAM GENERATING APPARATUS

Filed March 23, 1921

UNITED STATES PATENT OFFICE.

HENRY H. MERCER, OF CLAREMONT, NEW HAMPSHIRE, ASSIGNOR TO SULLIVAN MACHINERY COMPANY, A CORPORATION OF MASSACHUSETTS.

STEAM-GENERATING APPARATUS.

Application filed March 23, 1921. Serial No. 454,778.

My invention relates to channeling mechanisms and the methods of operating the same, and more particularly to apparatus for enabling getting up steam expeditiously 5 in oil fired steam channelers.

An object of my invention is to provide an improved channeler mechanism. Another object of my invention is to provide an improved system of operation for oil fired 10 channelers. A further object of my invention is to provide an improved type of oil fired channeler mechanism in which means is provided for storing in the channeler the requisite atomizing fluid for use during the 15 process of getting up steam. Other objects of my invention will appear in the course of the following specification and appended claims.

In the accompanying drawings I have 20 shown for purposes of illustration one form which my invention may assume in practice.

In these drawings,—

Fig. 1 is a side elevation of a channeler provided with one form of my improved 25 mechanism.

Fig. 2 is a view of a series of channelers each provided with mechanism for accomplishing my improved system of channeler operation and cooperating with a channeler 30 of the type shown in Fig. 1 for the purpose of storing up atomizing fluid.

In Fig. 1 of the accompanying drawings, I have illustrated a channeler comprising a channeling engine 1 adapted to be supplied 35 with steam from a boiler 2, said engine and boiler being mounted upon a truck 3 for movement upon wheels 4 along a track 5. The boiler is of a type in which there is provided a relatively large steam space at the 40 top thereof, the steam space being generally indicated by 6. The boiler is fired by means of fuel oil from a tank 7, and the oil is distributed by a pipe line 8 to a steam atomized oil burner 9, the supply of oil being 45 controlled by a stop valve 10. The supply of atomizing steam is adapted to be transmitted by a pipe line 11 from the steam space of the boiler and is controlled by either one of a pair of valves 12 and 13. The 50 valves 12 and 13 are located on opposite sides of a T 14 to which is connected, under the control of a stop valve 15, a pipe 16 leading from a T 17, there being provided a T 18 interposed in the pipe 16 adjacent the T 55 17. The opposite sides of the T 17 are con-

nected respectively by means of a pipe line 19 controlled by stop cock 20 with a receiver 21 and by a pipe line 22 controlled by a stop cock 23 with the cylinder of a high pressure air compressor 24. A branch line 25 provided with a stop cock 25' is connected to the T 18 between the T 17 and the valve 15 to permit the attachment of a hose as will later be described. A steam line for supplying fluid to any suitable motor, not shown, for operating the compressor 24 is illustrated at 26 and is controlled by a stop valve 27. It will be understood that, as desired, during the operation of the compressor 24 the boiler may be fired by means of oil passing through the burner 9 and atomized either by steam through the line 8 or by air passing through the line 16 and valves 15 and 13. The channeler so far described may be considered as the mother channeler.

The other channelers are similar to the channeler just described and comprise (see Fig. 2) frames 3 mounted on wheels 4 and the frames carry thereon boilers 2 and a channeler engine 1 identical in construction 50 with those described above. In the case of these channelers, however, the air compressor is not provided and the system consists, with the exception of the third channeler from the left which is later described, only 55 of a line 8 for the supply of oil fuel through a valve 10 to the oil burner 9 and of a pipe 11 having stop cocks 12 and 13 on opposite sides of the T 14, with which a pipe 28 communicates. The pipe 28 on each of these 60 channelers is connected by suitable hose 29 with pipe line 30 which connects with the discharge line 25 on the first mentioned or mother channeler. The operation of the system described is as follows: After the 65 channelers have worked all day and it is time to shut them down, the boilers are blown down in the well-known manner and then 70 filled up to the desired point. The burners are then extinguished and as soon as the 75 generation of steam has ceased and the steam spaces of the boilers are not filled with steam under pressure, the connections 29 are made with the pipes 28. The stop cocks 12 on 80 each of the channelers except the mother channeler are opened and the air compressor 24 having been started, air pressure sufficient 85 to cause popping of the safety valve is pumped up in the steam spaces of each of the 90 boilers. The valves 12 having been 95 100 105 110

closed, the various channelers are then disconnected from the hose connections 29 and suitable caps may be applied to the ends of the pipes 28 or these pipes may be provided with supplemental valves 31 to prevent escape of pressure therefrom. It will be understood that the large quantity of water in the boilers does not entirely cool over night and that by reason of the relatively great heating surfaces provided by the fire tubes and the relatively great heat which may be generated by means of the oil burners, steam may be gotten up quite rapidly after the boilers have stood over night. For the purpose of getting up steam, the valves 12 and 13 are opened and the air pressure is allowed to discharge at a very gradual rate through these valves to atomize the oil. Before the pressure stored in the steam spaces of the boilers has been wholly used for the purpose of the atomization of the oil supply to the burners, the boilers will again be steaming and the steam may be led through the same pipe 11 without cessation to continue the atomization of the oil supply to the burners. The air stored in one boiler may be used for the purpose of effecting atomization of oil in the furnaces of other boilers as well as in its own furnace.

As to the mother channeler, the method of shutting down is similar with the exception of the fact that in the case of this channeler it is necessary to store the reserve air for starting operation of the burners in the receiver 21, for obviously it would be impossible to pump the steam space in the boiler full of air by means of the steam in that boiler.

From the foregoing description the mode of operation of channelers used according to this system will be readily apparent and it will be evident that means is provided for causing the ready starting of oil burners, even though they may use a relatively poor grade of fuel oil, and it will further be obvious that the mechanism employed is of very simple construction and requires on most of the channelers the addition only of a T connection and one or two additional stop cocks. To regulate the pressure of the air supplied for atomization purposes a pressure reducing valve 32 may be installed in the line 11', and also a by-pass to permit the ready passage of air in the opposite direction if necessary.

It must be understood that my invention is not limited to use with fluid atomized burners and that by suitable modification it may be readily adapted to use with burners making use of mechanical means of atomization. With such a system (see the third channeler from the left in Fig. 2) the connection 11 would be dispensed with and a suitable burner 9' of the mechanical atomization type having been substituted for the

burner 9, the only other change required would be the provision of a small storage tank 33 for fluid pressure connected with the top of the oil tank 7 by way of a pressure reducing valve 32 and a stop valve 34 and provided with a valve controlled connection 35 for attachment to the hoses 29.

While I have in this application specifically described certain concrete embodiments which my invention may assume in practice and by which it may be carried out, it will be noted that these have been adopted for purposes of illustration only and that the invention may be modified and embodied in other forms without departing from its spirit or the scope of the appended claims.

What I claim as new and desire to secure by Letters Patent is:—

1. In a steam generating apparatus, a plurality of oil fired steam generating devices each having a steam storage chamber and an oil atomizer burner, means including a pump carried by one of said devices for filling the storage chambers of the others of said devices with compressed fluid after the generation of steam in said latter devices has ceased, a fluid receiver carried by the device which carries the pump, said pump being adapted to fill said receiver with compressed fluid, means for driving said pump, means for supplying compressed fluid from said receiver to said pump-carrying device for atomizing the oil for starting the same, and means for supplying the compressed fluid stored in said chambers of the other devices for atomizing the oil for starting the same.

2. In a steam generating apparatus, a plurality of oil fired steam generating devices each having a steam storage chamber and an oil atomizer burner, means including a pump carried by one of said devices for filling the storage chambers of the others of said devices with compressed fluid after the generation of steam in said latter devices has ceased, a fluid receiver carried by the device which carries the pump, said pump being adapted to fill said receiver with compressed fluid, means for driving said pump by the steam generated in the device by which it is carried, means for supplying compressed fluid from said receiver to said latter device for atomizing the oil for starting the same, and means for supplying the compressed fluid stored in said chambers of the other devices for atomizing the oil for starting the same.

3. A self-contained unit comprising a plurality of oil fired steam devices each including an oil atomizer burner, means including a pump carried by one of said devices and a receiver carried by one of said devices and chambers comprising steam spaces in the remainder of said devices for the supply of pressure fluid for use in effecting atomiza-

tion of the oil when it is desired to start up the devices after they have been shut down with the fires extinguished and steam generation terminated, and means whereby said pump is operated to generate pressure for said chambers.

4. A channeler equipment for quarries comprising a self-contained unit consisting of a plurality of steam driven oil fired channelers, means carried by each of said channelers for the storage of fluid pressure for use in effecting the atomizing of oil during the starting of said channelers after they have been shut down and steam generation has ceased, and means carried by one of said channelers for the production of fluid pressure for storage in said means.

5. The method of operating a self-contained channeler unit consisting of a plurality of oil fired steam devices comprising pumping up a pressure in a receptacle normally employed for steam in one of said channeler units subsequent to the cessation of steam generation therein, and employing the pressure so pumped up in the atomization of oil in all of said remaining channelers when started up.

6. The method of operating a series of oil fired boilers which consists in pumping

with steam from one of said boilers a substantially non-condensing pressure fluid into the steam space of another boiler so that fuel oil for said latter boiler may be atomized for starting after the same has been shut down.

7. The method of operating a series of oil fired boilers which consists in pumping with steam from one of said boilers a substantially non-condensing fluid under pressure into the steam space of another boiler and into a reserve tank for use with the first named boiler, so that fuel oil for said boilers may be atomized for starting after the same have been shut down.

8. A self-contained unit comprising a plurality of oil fired steam pressure devices, pressure generating means actuated by steam pressure from one of said devices for creating another fluid pressure, means for relieving steam pressure in the remaining devices and stopping the fires, and conduit means connecting said generating means with said relieved pressure devices for starting up said devices after the fires have been extinguished.

In testimony whereof I affix my signature.

HENRY H. MERCER.
